US00D918876S

(12) **United States Design Patent** (10) **Patent No.:** **US D918,876 S**
Mai (45) **Date of Patent:** **** May 11, 2021**

(54) **MICROPHONE**

(71) Applicant: **SHENZHEN XUNWEIJIA TECHNOLOGY DEVELOPMENT CO., LTD**, Shenzhen (CN)

(72) Inventor: **Qibin Mai**, Shenzhen (CN)

(73) Assignee: **SHENZHEN XUNWEIJIA TECHNOLOGY DEVELOPMENT CO., SHENZHEN**, Shenzhen (CN)

(**) Term: **15 Years**

(21) Appl. No.: **29/735,250**

(22) Filed: **May 19, 2020**

(51) LOC (13) Cl. **14-01**

(52) U.S. Cl.

USPC **D14/227**

(58) **Field of Classification Search**

(57) **CLAIM**

The ornamental design for a microphone, as shown and described.

DESCRIPTION

FIG. 1 is a front, right side, top perspective view of a microphone showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depict portions of the microphone that form no part of the claimed design.

1 Claim, 8 Drawing Sheets
